UNITED STATES PATENT OFFICE

ADOLPH F. SOBEN, OF LOS ANGELES, CALIFORNIA, ASSIGNOR TO HENRY H. DAVIS,
OF LOS ANGELES, CALIFORNIA

SECTIONAL DISPLAY CONTAINER

Application filed May 10, 1929, Serial No. 361,909. Renewed January 4, 1932.

My invention relates to containers, and more particularly to those containers that are adapted to be sealed under vacuum conditions, and then unsealed, one portion of said container, when unsealed, being adapted to function as a cover, the other portion of said container housing commodities, such as candy, candy bars, and the like, or other materials, being adapted to function as a display device.

As it well known, candy, candy bars, and the like, soon deteriorate in quality when exposed to the moisture in the air, and this is especially so when shipped, as, for example, when used on war ships, liners, or other vessels. Moreover, when such commodities are shipped in cans they are frequently crushed, due to rough usage. Again, the cans may not be effectively sealed, with the result that moisture penetrates said cans, resulting in the spoiling of the materials housed therein. By the use of my invention all these objectionable features are effectively eliminated.

It accordingly is an object of my invention to provide a novel form of container, preferably composed of upper and lower sections, forming a closure, temporarily sealed together under vacuum conditions, which seal is adapted to be removed, whereupon the upper section functions as a cover, said container having an inner shell, open at the top, and permanently secured at its bottom to said closure, and spaced therefrom, to provide for a moisture receiving space, which, even when said seal has been removed, will effectively prevent the moisture from reaching the materials in said inner shell, which space also functions to prevent the container from being crushed, and also prevents mutilation of the display wrapper enveloping or on said inner shell.

The above, and further objects and advantages of my invention, as will herein after more fully appear, I attain by the construction described in the specification, and illustrated on the drawing forming a part of my application.

Reference is had to the accompanying

drawing, in which similar reference characters denote similar parts. In the drawing,

Fig. 1 is a perspective view of my container, sealed and ready for shipping.

Fig. 2 is a cross sectional view, taken on the line 2—2, Fig. 1.

Fig. 3 is an enlarged, fragmentary sectional view, taken on the line 3—3, Fig. 2.

Fig. 4 is a perspective view of the container after it has been unsealed and the upper section or cover removed, showing the materials housed therein, said portion functioning as a display device.

Fig. 5 is a similar view of the upper section or cover.

Fig. 6 is a cross sectional view, taken on the line 6—6, Fig. 2, and

Fig. 7 is a perspective view of a modified form of container.

Describing my invention more in detail, it is my object to provide a sectional container sealed under vacuum conditions, which seal is adapted to be removed, so that one of said sections will function as a cover for an inner shell, permanently secured at its bottom to the outer shell or closure, said inner shell being open topped, and of substantially smaller length and volume, and spaced from said closure, to provide a moisture receiving space, to prevent said container from being crushed in shipping, said inner shell, when said container is unsealed, functioning as a display device, an advertising wrapper or label enveloping said inner shell, which wrapper or label is prevented from being mutilated by reason of the peculiar construction of said container.

More specifically, my invention comprises a container, designated generally by the reference numeral 2, which container is adapted to bear the usual advertising wrapper or label, and is preferably composed of an outer shell or closure having an upper section 4, and a lower section 6, sealed together under vacuum conditions by the seal 8, which in practice may be of conventional or other form, and is adapted to be removed by any means desired; and when so removed, said upper section forms a cover adapted to exclude dust, flies, and the like, from the lower section,

which is also adapted to function as a display device. See Figs. 4 and 5.

Positioned within the outer shell or closure, is an inner shell or compartment 10, which is open topped, and of substantially 5 smaller length and volume, and is offset at its lower end, as at 12, to provide a space 14 thereabout, which space functions to prevent the container from being crushed in shipping, or when roughly handled, and also as a moisture receiving space, to prevent said moisture reaching the materials 16 housed in said inner shell or compartment, even when said container has been opened. Said space also effectively prevents the advertising wrapper 10 or label on said inner shell from being mutilated. If desired, the upper end of the inner shell 10 may be provided with a curled end or flare 18, to facilitate the reception of the upper section or cover 4, and also to prevent mutilation of the display wrapper or label when said cover is put on or removed.

As seen more particularly in Fig. 3, the inner shell or compartment 10 has its bottom outwardly flared as at 20, and the lower section 6 of the outer shell or closure is also outwardly flared as at 22, the bottom 24 of said outer shell being curled over the said two flares as at 26, to effectively secure the inner shell or compartment to the lower section of the outer shell or closure.

It will, of course, be understood that the container may house any material in practice preferred, and that said container may be constructed of any desired material, or be of any desired shape or configuration. Such an alternative form is depicted in Fig. 7, wherein the container is of square or rectangular form.

While I have thus described my invention with great particularity, it will be clear that it is susceptible of a wide variation in construction. I accordingly do not propose to be limited to the exact details of construction shown and described, but reserve the right to make any and all modifications that fall within the scope of the appended claims.

I claim as my invention:

1. A container comprising an outer sectional closure, a diametrically smaller compartment within said closure, and provided with top and bottom outwardly directed flares, a bottom plate uniting the lower section of said outer closure and the bottom 55 flare of said smaller compartment, and a removable seal conjoining the sections of said outer closure.

2. A container adapted to be exhausted of air comprising a two part closure, an open 60 topped chamber within and spaced from said closure, the bottom of said chamber flaring outwardly, a bottom plate uniting the lower section of said outer closure and the flaring portion of said chamber, and means removably conjoining the sections of said outer

closure, the upper section of said outer closure, when disjoined from the lower section forming a cover for said chamber.

3. A container comprising a two part closure, a chamber within said closure provided with outwardly flaring top and bottom portions, spacing the chamber from said closure, a bottom plate conjoining the outwardly flaring bottom portion of the chamber with one part of said closure, and a removable seal 70 conjoining the parts of said closure.

4. A container comprising a sectional closure, a compartment within said closure and being of less longitudinal extent and diametrically smaller than said closure, a bottom plate conjoining the bottom of said compartment and one of the sections of said closure, and a removable seal uniting the sections of said closure, the upper section of said closure when disjoined from the lower 80 section forming a cover for said compartment.

5. A container comprising a sectional closure, a compartment within and spaced from said closure, the bottom of said compartment 90 provided with an outwardly directed flange, a bottom plate conjoining one section of said closure and the flange of said compartment, said compartment provided at the top with an outwardly directed flare arranged for contact with said closure to reinforce same, and a removable seal conjoining the sections of said closure.

6. A container comprising an outer shell and an inner shell secured together at their bottoms, said inner shell being of substantially smaller length and volume than said outer shell, a substantial portion of said inner shell being spaced from said outer shell to prevent said container from being crushed 100 in shipping.

7. A container comprising a removable outer shell and an inner shell secured together at their bottoms, said inner shell being spaced from said outer shell, a display wrapper on said inner shell, and means on the upper end of said inner shell to prevent said wrapper from being mutilated when said outer shell is removed and functions as a cover for said inner shell.

8. A display container comprising an outer open ended structure with outwardly flared ends, an inner open ended structure, also having flared ends, a bottom for both of said structures having its outer periphery crimped about the lower ends of each of said structures, and a top crimped about the upper flared end of said outer structure.

9. A display container comprising a sectional outer section, an inner section of substantially less length than said outer section, said inner section having an inwardly off-set wall, a closure for the top of said container and a closure for the bottom of said container, said inner section having its lower 125

end permanently secured to said outer section, said outer section having one of its sections adapted to be unsealed whereby said off-set wall will receive the upper part of said outer section as a cover.

5 In testimony whereof I have signed my name to this specification.

ADOLPH F. SOBEN.
